A. C. SHORTE AND H. B. TODD, OF PLYMOUTH, CONNECTICUT.

Letters Patent No. 86,039, dated January 19, 1869.

IMPROVEMENT IN MILK-CANS.

The Schedule referred to in these Letters Patent and making part of the same.

To all whom it may concern:

Be it known that we, A. C. SHORTE and H. B. TODD, of Plymouth, in the county of Litchfield, and State of Connecticut, have invented a new and useful Improvement in Milk-Cans; and we do hereby declare that the following is a full, clear, and exact description thereof, which will enable others skilled in the art to make and use the same, reference being had to the accompanying drawings, forming part of this specification, in which—

Figure 1 represents a side elevation of our improved can, with a part broken away, and

Figure 2 represents a plan view of the inside of the cover.

Similar letters of reference indicate like parts.

This invention relates to an improvement in milk-cans; and

It consists of a spring-locking device for securing the cover, as will be hereinafter described.

A represents the can, having an internal cylinder, as shown at B, to provide a space, C, which we propose to fill with pounded charcoal, or other similar substance, to prevent the heat of the atmosphere penetrating to the milk, which is designed to be put in at a low temperature.

The cover is provided with spring-hooks *a*, so arranged, as to hook under the shoulder of the can, at *b*, when extended to secure it to the can.

D represents a cover for the tube *f*.

To actuate the springs, the cover is provided with a cross-bar, *d*, which supports a vertical shaft, *e*, in a tube, *f*, projecting downward from the top of the cover, and

opening through the cover at the top, to admit a wrench for turning the said shaft.

The lower end of the shaft, above the cross-bar, is provided with arms *g*, projecting horizontally on opposite sides, and connected by toggle-joints *h* to the spring-hooks *a*.

The tendency of the spring-hooks is to the inward or unhooked position, as represented in fig. 2; and to hook the cover to the can, the shaft must be turned by the key in the direction to straighten out the toggle-joints, which will press the springs outward; and in order to cause the hooks to remain in the locked condition, it is necessary to carry the toggle-joints a little beyond the straight line, as shown in red, when the inward pressure of the springs will bear the arms *g* against the pins *i i*, and they will thereby be maintained in the locked position, until turned back again beyond the radial line by the key, when they will spring inward far enough to release the covers.

Having thus described our invention,

We claim as new, and desire to secure by Letters Patent—

The combination, with the spring-hooks *a* secured to the cover *B*, of the shaft *e* connected to them by toggle-joints, and provided with the stop-pins *i i*, substantially as and for the purpose described.

A. C. SHORTE.
H. B. TODD.
